UNITED STATES PATENT OFFICE.

MYRON ORTON, OF VINELAND, NEW JERSEY.

THEATRICAL APPLIANCE.

1,301,963.

Specification of Letters Patent. Patented Apr. 29, 1919.

Application filed May 8, 1917. Serial No. 167,169.

To all whom it may concern:

Be it known that I, MYRON ORTON, a citizen of the United States, residing at Vineland, county of Cumberland, and State of 5 New Jersey, have invented a certain new and useful Theatrical Appliance, of which the following is a specification.

This invention is a theatrical appliance, and is more particularly directed to means 10 for carrying out a performance in which two or more parties are enabled to run a foot race on a plurality of tight ropes.

The object of the invention is the provision of a plurality of endless tight ropes, on 15 each of which an artist is adapted to perform, the tight ropes being so mounted that when the artist runs, the corresponding tight rope will be moved by the operator, who will maintain a substantially fixed position, 20 the relative movement between the artist and the tight rope being taken up by movement of the latter.

A further object of the invention is the association with each tight rope of means for 25 indicating the speed or extent of movement of each tight rope, whereby the operations of the two or more artists are recorded in plain view of the audience, so that relative speeds attained by said performers or the 30 distance traversed by them may be followed.

In one of its preferred, practical forms, the invention embodies a plurality of endless tight ropes mounted side by side, and stretched about spaced sheaves or supporting 35 wheels. With each tight rope is associated an indicator operatively connected through suitable mechanism with one of the sheaves which supports the tight rope. A plurality of artists are adapted to mount several tight 40 ropes and, figuratively speaking, to run a race, one artist performing on each rope. The operations of each artist are recorded through the means specified by the recorder associated with his tight rope so that the 45 audience viewing the operations of all of the performers simultaneously can ascertain, by a glance at the indicators, the result of the race.

Features of the invention, other than those 50 specified, will be apparent from the herein-after detailed description, when read in conjunction with the accompanying drawings.

In the accompanying drawings, I have 55 illustrated one practical embodiment of the invention, but the construction therein shown

is to be understood as illustrative, only, and not as defining the limits of the invention.

Figure 1 is a perspective view of an appliance embodying the present invention, two performers being shown in the act of 60 carrying out the race.

Fig. 2 is an end elevation of the preferred form of horse for supporting one of the sheaves and the indicator associated therewith.

Fig. 3 is a like view of the horse for supporting the other sheave, and

Fig. 4 is a detail edge elevation of the preferred form of means employed for mounting the sheaves on the horses.

Referring to the drawings, A and A' indicate two endless flexible tight ropes. The tight rope A extends around a pair of spaced sheaves B and C, while the tight rope A' extends around similar sheaves B' and C'. 70 The sheaves B and B' are supported on horses D and D', while the sheaves C and C' are carried by horses E and E'. The tight ropes are maintained in a substantially taut condition by guy ropes d d' and e e'. 80 Guy ropes d and d' are secured to halters F F' mounted on the horses D D' respectively, and guy ropes e e' are secured to halters G G' mounted on horses E E', respectively.

Mounted on the horse D and associated with the sheave B is an indicator I, and a similar indicator I' is mounted on the horse D' and is associated with the sheave B'. The horses E E' are substantially the same 90 in construction, the which is detailed in Fig. 3 and the horses D D' are also the same in construction, the which is shown in Fig. 2. Accordingly, in the following description where the construction of Figs. 2 95 and 3 is described, more particularly with relation to the horses D E' respectively, it will be understood that the construction of the horses D E will be satisfied by the same description.

Horse D', shown in Fig. 2, may be of any structural design adapted for the use, but is here shown as in the form of a cast or built-up metal frame having two legs j and connecting bracing k. The sheave B' is 105 mounted on an axle b for rotation within bearings supported on the legs j. In view of the fact that the present invention is intended, more particularly, for theatrical troupes, it is desirable that the structure be 110

demountable, and, there is shown in Fig. 4 a form of bearing which is recommended in this environment. Each bearing embodies a fixed portion J cast integral with, or secured 5 to, one leg. The fixed portion J is open at one side to allow of the positioning of the axle b within, or the removal of said axle from, the bearing, the axle being normally maintained within the bearing by means of 10 a pivoted portion K pivotally secured to the portion J, as at l, and having at its opposite end an apertured ear l' adapted to be brought into coöperative relation with corresponding ears k' and a pin passed through 15 the thus aligned apertures k' to lock the axle in place within the bearing. The axle may, however, be readily removed by drawing the pin and swinging back the pivoted member K of each bearing. This easily detachable 20 construction is very advantageous, since it allows of the ready removal of the endless tight rope from any sheave desired.

The horse D', thus far described, is identical with the horse E of Fig. 3, which 25 supports the sheave C', except that it is preferred, in practice, to make the horse D', toward which the operator faces, slightly higher than the horse E' at his back, so that in his performance, he, in effect, runs up 30 hill. This is found to give the best results. As shown in Fig. 1, however, the horse E is of a slightly greater height than the horse D, for the same reason. Except for 35 these differences in height between the respective horses, the constructions of all are the same aside from the fact that means is provided on the horse D' for mounting the indicator I', and on the horse D for mounting the indicator I. The preferred method 40 of attaching the halters is clearly shown in Figs. 2 and 3, where the halter F' is shown as secured to the horse D', and the halter G' as secured to the horse E'.

The method of mounting the indicators 45 I I' is clearly shown in Fig. 2, and consists in providing the associated horse with an upstanding arm M provided, at its upper end, with a bracket m adapted to be secured to the rear of the dial i of the indicator. A 50 shaft or spindle m' is journaled in the arm M, and carries at its other end a pointer i'. On the spindle m' is fixed a worm-wheel n, and a worm n' is fixed upon the axle b which carries the sheave B'. A vertical shaft O, 55 journaled in brackets o on the leg j and arm M, carries, on its upper end, a worm o' and at its lower end a wheel o'', so that when the sheave is rotated, such rotation is imparted through the connections specified to the 60 pointer i' for the purpose of moving said pointer about the face of the dial. The relative movement between the pointer and the sheave is so worked out by the worms and worm-wheels that the circumferential 65 travel of said sheave will be indicated by the

pointer. That is to say, that if the sheave is one yard in diameter, the gearing between the parts may be such that one rotation of the sheave will register one yard on the indicator. Of course, this example is illustrative only, but will serve to explain the manner in which the performance of the artists will be recorded. 70

As hereinbefore stated, one of these indicators is associated with each tight rope, 75 so that a glance at the indicator will immediately show how far or how fast the several performers have or are traveling.

In carrying out the performance the artists may run fast or slow, as desired, and 80 their gravity; running up hill as it were, causes the respective tight ropes to travel and the sheaves to revolve. There is no power used to turn the wheels other than that of gravity or the power of the legs of 85 the artists, so that the artists are not forced, in any way, but act upon their own incentive entirely.

Throughout the foregoing specification and appended claims, the term "tight rope" 90 is used generically, and it is to be understood that this tight rope may be of fiber, metal, or any other suitable material.

Having thus fully described the invention, what I claim as new, and desire to secure by 95 Letters Patent, is:

1. A theatrical device for tight rope racing embodying a pair of sheaves spaced apart and one of which is positioned at a higher elevation than the other, an endless 100 flexible tight rope encircling the sheaves and on which tight rope a performer is adapted to run, for the purpose of imparting longitudinal movement to the tight rope, and means associated with one of the sheaves for 105 indicating the distance traveled by the runner.

2. A theatrical device adapted for tight rope racing embodying a pair of supports spaced apart, a sheave mounted for free rotation on one of said supports, a second sheave mounted, at a higher elevation than the first sheave, for free rotation on the other of said supports, and an endless flexible tight rope encircling the sheaves, where- 110 by when a performer runs upon the rope the rope is caused to travel around the sheaves. 115

3. A theatrical device for tight rope racing embodying a pair of horses spaced apart, 120 a sheave rotatably mounted on each horse, the sheave on one horse being at a higher elevation than the sheave on the other horse, an endless flexible tight rope stretched between the sheaves, and an indicator asso- 125 ciated with one of the sheaves for indicating the travel of the tight rope when actuated by an artist performing thereon, in combination with a second pair of horses spaced apart, a sheave rotatably mounted on each 130

horse and one of which sheaves is positioned at a higher elevation than the other, a tight rope stretched between said sheaves, and indicator means associated with one of the 5 sheaves for indicating the travel of the tight rope when actuated by the second artist performing thereon, whereby an audi-

ence may determine by watching the indicators the comparative speeds at which the two artists are performing and the distances 10 traveled by them.

In testimony whereof I have signed my name to this specification.

MYRON ORTON.
